UNITED STATES PATENT OFFICE.

FRIEDRICH WILHELM MROSE, OF COESFELD, GERMANY.

SAFETY-STIRRUP.

SPECIFICATION forming part of Letters Patent No. 537,219, dated April 9, 1895.

Application filed January 15, 1895. Serial No. 535,033. (No model.)

To all whom it may concern:

Be it known that I, FRIEDRICH WILHELM MROSE, a subject of the King of Prussia, German Emperor, residing at Coesfeld, in the 5 Empire of Germany, have invented certain new and useful Improvements in Safety-Stirrups, of which the following is a specification.

The present invention relates to an improved stirrup by which its entanglement 10 with the foot of the rider in case of accident, such as the fall of the rider or horse, or in mounting or dismounting, is prevented.

The improved stirrup differs from others having the same object, in the method of construction by which to obtain the required result, the tread of the stirrup being made in 15 two halves, which, by the pressure of the rider's foot when caught in it, turn sidewise and thereby open, while after the foot is freed 20 from the stirrup, the parts return automatically to their normal position.

The accompanying drawings are in illustration of the invention.

Figure 1 is a longitudinal section through 25 a stirrup, and Fig. 2 is a transverse section, showing the bottom plate or tread.

The upper part or bail *a* of the stirrup is somewhat larger in cross section than the side pins *b b* projecting down from its lower ends, 30 upon which the tread made in two parts *c c* fits, these parts being provided with sockets *c' c'*, which turn upon the pins *b b*.

The upper edges of the sockets *c'*, are inclined to their axis, and fit against corresponding 35 sockets or rings *d* the lower edges of which are similarly inclined or beveled, and which are movable in a longitudinal direction only, being guided by a pin *d'* fitting in the slot *d*'. These sockets *d* are pressed down by helical 40 springs *e* the upper ends of which abut against the projecting edge of the bail *a*, of the stirrup, and in this way the halves of the tread *c c* are kept in their proper normal position.

In order to reduce the friction of the sockets *c' c'* upon the halves of the tread in turning, the lower ends of these sockets are fitted 45 with antifriction balls *f* which are supported by a flange upon the head *g'* of a screw *g* screwed into the lower end of the pins *b*. The 50 whole of the parts surrounding these pins are covered by a sheath or casing *i*.

In order to insure the retention in position of the two movable halves *c* of the tread de-

scribed, there is fixed upon one of them a spring safety plate *h*, having beveled lower 55 flanges at its sides, which fit against corresponding projecting edges upon the parts *h' h'* of the halves of the tread, so that while the foot of the rider is pressing properly upon the stirrup, the parts are kept in their normal 60 position, but when from accidentally becoming entangled the foot presses against the sides of the tread, the latter open out laterally, (as shown in dotted lines in Fig. 2.)

The operation of the improved stirrup is as 65 follows: If the foot of the rider from any cause, such as a fall, becomes caught in the stirrup, a side pressure is exerted by the heel or toe against the tread of the stirrup. As this pressure is greater than that exerted by 70 the two springs *e*, it follows that the halves of the tread, after the safety plate *h* has been released from the projections *h'* in the way already described, can turn around laterally, (as shown by the arrows and dotted lines in 75 Fig. 2.) The sockets *d*, by reason of their inclined edges which fit against the corresponding ones on the tread sockets *c'*, are forced upward, compressing the springs *e*. After the halves of the stirrup tread are sufficiently 80 opened and the foot released, they are at once returned to their original closed position, by the action of the springs upon the inclined edges of the sockets. The safety plate *h* therefore again becomes engaged with the projections at *h'* upon the two halves of the 85 tread *c*.

Having now particularly described and ascertained the nature of my said invention and in what manner the same is to be performed, 90 I declare that what I claim is—

1. A safety stirrup composed of a bail and of a divided, spring-actuated tread, pivoted to the bail, substantially as specified.

2. The combination of a bail *a*, with pins 95 *b*, beveled sockets surrounding the same, beveled spring actuated rings engaging the sockets, a divided tread supported by the pins and a foot plate that is adapted to extend over the tread-joint, substantially as specified. 100

Signed at Dusseldorf, Germany, this 29th day of December, 1894.

FRIEDRICH WILHELM MROSE.
